UNITED STATES PATENT OFFICE

96,305

DESIGN FOR A DRESS

Frances Giordano, New York, N. Y.

Application March 21, 1935, Serial No. 55,985

Term of patent 7 years

To all whom it may concern:

Be it known that I, Frances Giordano, a citizen of the United States, and resident of the city of New York, in the county of New York and State of New York, have invented a new, original, and ornamental Design for a Dress, of which the following is a specification, reference being had to the accompanying drawing, forming part thereof, in which

Fig. 1 is a front view of the dress of my invention.

Fig. 2 is a rear view of the dress of my invention.

Fig. 3 is a detailed front view of the blouse portion of the dress showing the dress collar in open position.

I claim:

The ornamental design for a dress substantially as shown.

Dated: March 20th, 1935.

FRANCES GIORDANO.
